[57] CLAIM

The ornamental design for a direction finding radio receiver, as shown and described.

DESCRIPTION

FIG. 1 is a top and front perspective view of a direction finding radio receiver showing the new design;

FIG. 2 is a right side elevational view;

FIG. 3 is a front elevational view;

FIG. 4 is a rear elevational view;

FIG. 5 is a left side elevational view;

FIG. 6 is a top plan view;

FIG. 7 is a bottom and front perspective view of a direction finding radio receiver showing a modified form of my new design with a top mounted bracket and downward tilting front panel;

FIG. 8 is a left side elevational view thereof; and

FIG. 9 is a bottom plan view thereof.

FIG. 1

FIG. 2

FIG. 3

FIG. 4

FIG. 5

FIG. 6

FIG. 7

FIG. 8

FIG. 9
